UNITED STATES PATENT OFFICE.

CHARLES F. STODDARD, OF BOSTON, MASSACHUSETTS, ASSIGNEE TO AMERICAN PNEUMATIC SERVICE COMPANY, OF DOVER, DELAWARE, A CORPORATION OF DELAWARE.

PNEUMATIC-DESPATCH-TUBE APPARATUS.

992,822.

Specification of Letters Patent.

Patented May 23, 1911.

Application filed July 25, 1908. Serial No. 445,406.

To all whom it may concern:

Be it known that I, CHARLES F. STODDARD, of Dorchester, Boston, in the county of Suffolk and State of Massachusetts, have invented certain new and useful Improvements in Pneumatic-Despatch-Tube Apparatus, of which the following is a specification.

My invention relates to improvements in pneumatic despatch tube apparatus and especially to a means for preventing the despatching of carriers at too short intervals, and commonly called a time lock. I have shown the time lock connected to a pneumatic tube sending terminal such as is described in my Patent No. 742513 dated Oct. 27, 1903.

In the accompanying drawings which illustrate a construction embodying my invention, Figure 1 is a longitudinal cross section showing the parts in their normal positions. Fig. 2 is a similar view showing the parts in the positions they would assume just as a carrier is being inserted in the sending terminal. Fig. 3 is a similar view showing the position of the parts after the carrier has left the sending terminal and before the time lock has unlocked the tripping mechanism to permit another carrier to be despatched. Fig. 4 is an enlarged detail sectional view of the needle-valve mechanism.

Like letters of reference refer to like parts throughout the several views.

The transmission tube A is in communication with the supply pipe A' through the casing A² provided with slots A³. Secured to this slotted casing A² is a sender B composed of three chambers B', B², B³. Secured to the upper chamber is a chute C; swinging on the shafts D D' in the chambers B', B³ are the counterweighted valve arms D² D³ to which are fastened the gates D⁴ D⁵ by the pins D⁶ D⁷. Just below the outer or upper gate D⁴ is the port E which is normally closed by the valve E' held in closed position by the spring E². The opening of the valve E' is controlled by the finger E³ placed just above the gate D⁴ in the chamber B' and pivoted to the chamber B' by the pin E⁴. The rod E⁵ pivoted to the finger E³ by the pin E⁶ connects the finger E³ with the valve E'. The by-pass port F connects the inside of the chamber B³ below the gate D⁵ with the chamber B² above

the gate D⁵ and is of an area much smaller than the area of the port E so that when the port E is open to the atmosphere, the port F cannot supply pressure fast enough to overcome the leakage through the port E and the pressure in the chamber B² remains at about atmospheric.

The trip finger H is pivoted to the chute C by the pin H' and normally held in the position shown in Fig. 1 by the spring H². The swinging arm J is pivoted to the chute C by the pin J' moved to the position shown in Fig. 3 by the spring J² which engages the swinging arm J at the point J³ and the chute C at the point J⁴. The cylinder K is secured to the chute C by the side plate K' and is provided with a piston K² to which is secured the plunger rod K³; the piston K² is thrown into the position shown in Fig. 2 by the spring K⁴.

The time lock cylinder L is provided with a floating piston L' and the upper end of the time lock cylinder L is connected to the atmosphere by port L⁷ and the lower end is connected to the chamber B² between the gates D⁴ and D⁵ by the pipe L⁴ in which is interposed the check valve L² and the by-pass needle valve L³. At a point near the upper end of the time lock cylinder is the port L⁶ connected to the lower end of the time lock cylinder by the pipe L⁵.

The operation is as follows: In Fig. 1 all the parts are shown in their normal positions and the transmitter is ready to despatch a carrier. A carrier is placed upon the chute C and by the force of gravity slides down against the trip finger H throwing it into the position shown in Fig. 2 and then down against the finger E³ throwing it into the position shown in Fig. 2 and thereby opening the valve E' and reducing the pressure in the chamber B² between the gates D⁴ and D⁵ to substantially atmospheric. The carrier X slides on down against the gate D⁴ opening same and entering the chamber B² and dropping against the lower gate D⁵ which is now being held closed by the pressure on the under side of it. After the carrier passes from under the gate D⁴ said valve assumes the position shown in Fig. 3 as do all the other parts. The valve E', now being closed, the pressure in the chamber B² is raised through the port F to the same as that on the under side of the gate D⁵ and the carrier X by its weight opens the

gate D⁵ and passes through the slotted casing A² into the transmission tube A. When the carrier X presses the finger E³ into the position shown in Fig. 2, thereby opening the port E to the atmosphere and reducing the pressure in the chamber B² to substantially atmospheric, the pressure in the lower end of the time lock cylinder L was also reduced to substantially atmospheric and the piston L' by its own weight quickly descends to the position shown in Fig. 2 and connects the lower end of the trip cylinder K with the atmosphere through the pipe L⁵ and the port L⁷, and allows the spring K⁴ to press the piston K² into the position shown in Fig. 2, and the plunger piston rod K³ in turn allows the spring J² to throw the swinging arm J against the trip finger H as shown in Fig. 2. When the carrier has passed over the trip finger H, the spring H² throws the trip finger H into the position shown in Fig. 3 and the spring J² presses the swinging arm up behind the shoulder H³ of the trip finger H thereby locking the trip finger H so that another carrier placed on the chute C could only slide down against the trip finger H. When the carrier passes down into the chamber B² and thereby allows the gate D⁴ and the valve E' to assume the positions shown in Fig. 3, the pressure in the chamber B³ under the gate D⁵ passes through the port F into the chamber B² above the gate D⁵ and equalizes the pressure on each side of the gate D⁵, and the carrier by its own weight opens the gate D⁵ and passes through the slotted casing A² into tube A. When the pressure passes into the chamber B² through the port F and makes the pressure in the chamber B² equal to that in the transmission tube A, said pressure is communicated through the pipe L⁴ to the lower end of the time lock cylinder L but is restricted by the check valve L² and governed by the by-pass needle valve L³ so that by the regulation of the needle valve L³ the time it takes the pressure to raise the piston L' to the position shown in Fig. 1 is predetermined. Until the piston L' reaches the top of the time lock cylinder L, the pipe L⁵ is connected to the atmosphere through the port L⁷, but when the piston L' passes the port L⁶ as it reaches the upper end of the time lock cylinder L it throws the lower end of the trip cylinder K into communication with the pressure of the transmission tube A through the pipe L⁴, the by-pass needle valve L³, the port L⁶ and the pipe L⁵ and this pressure forces the piston K² into the position shown in Fig. 1 thereby throwing the swinging arm J into the position shown in Fig. 1 and unlocking the trip finger H and completing the cycle of operation. The machine is now ready to receive another carrier.

Having thus described the nature of my

invention and set forth a construction embodying the same, what I claim as new and desire to secure by Letters Patent of the United States is:—

1. In a pneumatic despatch apparatus, a transmission tube, a sender connected to said transmission tube, inner and outer gates normally closing said sender, means for normally producing equalization of pressure in the transmission tube and the sender, an exhaust port from said sender to the atmosphere normally closed, an exhaust valve controlling said port to allow the pressure to exhaust from the sender for releasing the transmission tube pressure on the outer gate to permit the entrance of a carrier into the sender, means operated by the carrier for opening said exhaust valve, means for closing said exhaust valve after the entrance of the carrier to permit the pressure in the sender and the transmission tube to substantially equalize on the inner gate whereby the weight of the carrier will open said inner gate and enter the transmission tube, a trip-finger to control the entrance of a carrier into said sender, pressure-actuated mechanism communicating with said sender between said gates operating said trip-finger to release the carrier when the pressure in the sender equalizes the pressure in the transmission tube, and means interposed in the communication between said sender and said pressure-actuated mechanism to regulate the flow of pressure from the sender to the pressure-actuated mechanism to time the operation of said pressure actuated mechanism in moving the trip-finger to release the carrier. 100

2. In a pneumatic despatch apparatus, a transmission tube, a sender connected to said transmission tube, inner and outer gates normally closing said sender, means for normally producing equalization of pressure in the transmission tube and the sender, an exhaust port from said sender to the atmosphere normally closed, an exhaust valve controlling said port to allow the pressure to exhaust from the sender for releasing the transmission tube pressure on the outer gate to permit the entrance of a carrier into the sender, means operated by the carrier for opening said exhaust valve, means for closing said exhaust valve after the entrance of the carrier to permit the pressure in the sender and the transmission tube to substantially equalize on the inner gate whereby the weight of the carrier will open said inner gate and enter the transmission tube, a trip-finger to control the entrance of a carrier into said sender, pressure-actuated mechanism communicating with said sender between said gates operating said trip-finger to release the carrier when the pressure in the sender equalizes the pressure in the transmission tube, and means interposed in the communication between the sender and the pressure-actuated mechanism to regulate the flow of pressure from the sender to the pressure-actuated mechanism to time the operation of said pressure actuated mechanism in moving the trip-finger to release the carrier. 110

pressure-actuated mechanism to retard the flow of pressure from the sender to the pressure-actuated mechanism and to permit a free flow of the pressure from the pressure-
5 actuated mechanism to the sender.

3. In a pneumatic despatch apparatus, a transmission tube, a sender connected to said transmission tube, inner and outer gates normally closing said sender, means for normally producing equalization of pressure in the transmission tube and the sender, an exhaust port from said sender to the atmosphere normally closed, an exhaust valve controlling said port to allow the pressure to 10 exhaust from the sender for releasing the transmission tube pressure on the outer gate to permit the entrance of a carrier into the sender, means operated by the carrier for opening said exhaust valve, means for closing said exhaust valve after the entrance of the carrier to permit the pressure in the sender and the transmission tube to substantially equalize on the inner gate whereby the weight of the carrier will open said inner 15 gate and enter the transmission tube, a time-lock cylinder communicating at one end with said sender between said gates and having at the other end an external opening to the atmosphere, a floating piston in said time-lock cylinder, pressure-actuated mechanism communicating with said time-lock cylinder near the end of the cylinder open to the atmosphere, and a trip-finger to control the entrance of a carrier into the sender operated by said pressure-actuated mechanism to release the carrier when the pressure in the time-lock cylinder raises the floating piston to close the external opening of the time-lock cylinder and to open communication through said 20 cylinder between the pressure-actuated mechanism and the sender.

4. In a pneumatic despatch apparatus, a transmission tube, a sender connected to said transmission tube, inner and outer gates normally closing said sender, means for normally producing equalization of pressure in the transmission tube and the sender, an exhaust port from said sender to the atmosphere normally closed, an exhaust valve controlling said port to allow the pressure to exhaust from the sender for releasing the transmission tube pressure on the outer gate to permit the entrance of a carrier into the sender, means operated by the carrier for opening said exhaust valve, means for closing said exhaust valve after the entrance of the carrier to permit the pressure in the sender and the transmission tube to substantially equalize on the inner gate whereby the weight of the carrier will open said inner 45 gate and enter the transmission tube and to

hold said outer gate closed so that the pressure in the transmission tube will not escape into the atmosphere, a time-lock cylinder communicating at one end with said sender between said gates and having at the other end an external opening to the atmosphere, means for retarding the flow of pressure from the sender to the time-lock cylinder, a floating piston in said time-lock cylinder, pressure-actuated mechanism communicating with said time-lock cylinder near the end of the cylinder open to the atmosphere, and a trip-finger to control the entrance of a carrier into the sender operated by said pressure-actuated mechanism to release the carrier when the pressure in the time-lock cylinder raises the floating piston to close the external opening of the time-lock cylinder and to open communication through said 50 cylinder between the pressure-actuated mechanism and the sender.

5. In a pneumatic despatch apparatus, a transmission tube, a sender communicating with said tube, a time-lock cylinder communicating at one end with said sender and having at the other end an external opening to the atmosphere, pressure-actuated mechanism communicating with said cylinder near the end of the cylinder having the external opening to the atmosphere, a floating piston in said cylinder to control the communication of the pressure-actuated mechanism with the sender and with the external air, and a trip-finger to control the entrance of a carrier into the sender operated by said pressure-actuated mechanism.

6. In a pneumatic despatch apparatus, a transmission tube, a sender communicating with said tube, a time-lock cylinder communicating at one end with said sender and at the other end an external opening to the atmosphere, means for regulating the flow of pressure from the sender to the time-lock cylinder, pressure-actuated mechanism communicating with said cylinder near the end of the cylinder having the external opening to the atmosphere, a floating piston in said cylinder to control the communication of the pressure-actuated mechanism with the sender and with the external air, and a trip-finger to control the entrance of a carrier into the sender operated by said pressure-actuated mechanism.

In testimony whereof, I have signed my name to this specification in the presence of two subscribing witnesses, this fifteenth day of June A. D. 1908.

CHARLES F. STODDARD.
